2 SHEETS—SHEET 2.

UNITED STATES PATENT OFFICE.

CHESTER H. BEACH, OF RACINE, WISCONSIN, ASSIGNOR TO WISCONSIN ELECTRIC COMPANY, OF RACINE, WISCONSIN, A CORPORATION OF WISCONSIN.

SEWING-MACHINE MOTOR.

1,252,317.

Specification of Letters Patent.

Patented Jan. 1, 1918.

Application filed June 21, 1915. Serial No. 35,348.

To all whom it may concern:

Be it known that I, CHESTER H. BEACH, citizen of the United States, residing at Racine, in the county of Racine and State 5 of Wisconsin, have invented a certain new and useful Improvement in Sewing-Machine Motors, of which the following is a full, clear, concise, and exact description.

My invention relates to sewing machine 10 motors. One of its objects is to provide simple and efficient means whereby the ordinary driving belt of the machine can be utilized as the power transmission means for operatively connecting the shaft of the motor with the arm-shaft of the machine. Another object is to provide means whereby the opening and closing of the motor circuit, the driving connection between the motor and the sewing machine, and the various speeds at which the machine is adapted 20 to be driven by the motor may all be controlled through the treadle.

With the above objects in view, one feature of my invention relates to a switch- 25 controlling lever and to the means for operating the lever from the treadle. Another feature relates to the mounting of the belt adjusting pulley upon the switch-controlling lever, thereby likewise placing, under the 30 control of the treadle, the speed at which the machine may be driven by the motor. A further feature of the invention relates to the structure and location of the switch, the switch preferably comprising a blade which 35 is spring-pressed toward one of the brushes of the motor but normally separated therefrom by an insulating strip adapted to be inserted or withdrawn by the aforementioned switch-controlling lever.

40 My invention and the several features thereof may be more readily understood by reference to the embodiment thereof illustrated in the accompanying drawings, in which—

45 Figure 1 is a top plan view of a motor showing it in position upon the table-top of the sewing machine;

Fig. 2 is a detailed, plan view of a clamp employed in connection with my present invention, but forming the subject matter of another application;

Fig. 3 is a section on the line 3—3 of Fig. 2;

Fig. 4 is a section on the line 4—4 of 55 Fig. 1;

Fig. 5 is a longitudinal central section of one end of the motor; and

Fig. 6 is a section on the line 6—6 of Fig. 5.

Like reference numerals refer to like parts 60 throughout the several views.

The motor 1, which may be of any suitable type, has secured upon the underside of its base one member 2 of a clamp. The member 2 is L-shaped and the foot of the L is 65 provided with a transverse slot 3 for receiving a screw 4 by which said member 2 and a base-plate 5 are attached to the underside of the motor-frame. As shown in Figs. 1 and 4, the member 2 extends rearwardly 70 from the motor, and hence the slot 3 permits of the motor being adjusted to a slight extent either forwardly or rearwardly in order to locate the motor-shaft pulley 6 in proper position with respect to the driving 75 belt 7 of the sewing machine. The member 2, at its elbow, is provided with a downwardly extending portion 8 constituting one of the jaws of the clamp, said jaw, as shown most clearly in Fig. 4, projecting through 80 an opening 9 commonly provided in the table-top 10 for the belt 7. At its rear end the member 2 is provided with a headed stud 11 which passes through a slot 12 in the other member 13 of the clamp, thereby 85 holding the two members 2 and 13 together, with the member 13 slideable longitudinally of the member 2. At its rear end the member 13 is provided with a downwardly extending jaw 14 adapted to engage over the 90 rear end of the table-top. A coiled spring 15 serves to hold the jaws 8 and 14 in clamping relation with the table-top 10. It will be seen that by merely pulling the jaws 8 and 14 apart and inserting one of the jaws 95 in the opening 9 and the other over the rear edge of the table-top and then releasing the jaws, that the tension of the spring 15 will securely clamp the motor in position upon the machine. While the clamping means 100 just described provides a very convenient means for mounting the motor in position, my invention is not limited to such means, and, moreover, said clamping means, as hereinbefore stated, is disclosed and claimed by 105 me in another application for Letters Patent.

As shown most clearly in Figs. 1 and 4, the usual groove in the periphery of the motor-shaft pulley 6 is in position to receive 110

the driving-belt 7 of the machine, said driving-belt normally extending into the groove but out of operative engagement with the pulley 6. That is to say, the periphery of the pulley 6 is in substantial alinement with the peripheries of the arm-shaft pulley 16 and the belt pulley (not shown) of the sewing machine. Pivoted upon the end of the motor-frame, near the base thereof, is a lever 17 which extends upwardly and is curved rearwardly over the motor-shaft. At its free end the lever 17 carries a pulley 18, adapted, when the lever 17 is operated, to engage the belt 7 and move the same into operative relation with the pulley 6. The pulley 18 thus controls the operative engagement of the belt 7 with the pulley 6, whereby the driving of the belt 7 by the pulley 6 and the speed at which the sewing machine is driven are dependent upon the position of the pulley 18. When the pulley 18 is out of engagement with the belt 7, said belt is out of co-operative relation with the pulley 6. The lever 17 is normally held by a spring 19 in the inoperative position shown in Fig. 4. A chain 20 secured at one end to the lever 17 and at its other end to the treadle (not shown) of the machine permits of the lever 17 being operated through the medium of the treadle and being held at any position of its operation. The treadle may be, and preferably is, the usual foot treadle of the machine. The chain 20 extends over a guide-pulley 21 conveniently mounted upon the member 13 of the clamp, and the portion of the chain 20 which runs over the pulley is preferably in the form of a coiled spring 22 which provides a more suitable running surface and at the same time renders the chain 20 somewhat yielding.

The lever 17 is also utilized for operating the switch which controls the circuit of the motor. With this object in view, the lever 17 is provided with a pin 23 which projects through one of the usual ventilating openings in the end of the motor-casing. The pin 23 extends into a slot 24 in a plate of insulating material. Said plate of insulating material consists of a lower portion 25 in which the slot 24 is located and an upwardly extending strip 26 which extends through a guide-loop 27 upon the lower end of a flexible switch-blade 28. The spring tension of the blade 28 tends to press the same into contact with one of the brush-holders 29 of the motor, but the blade is normally separated from the brush-holder by the insulating strip 26. As shown in Figs. 5 and 6, one of the wires 30 of the motor circuit is secured to the switch-blade 28, while the other wire 31 is connected directly to the other brush-holder 32 of the motor. The motor circuit is thus normally held open by the strip 26 which is interposed between the switch-blade 28 and the brush-holder 29.

When a pull is exerted upon the chain 20 for the purpose of starting the motor, the pin 23 moves rearwardly and downwardly, and, sliding in the slot 24, draws down the insulating plate to the position indicated in dotted lines in Fig. 6, thereby permitting the switch-blade 28 to press into contact with the brush-holder. The lever 17 is thus operated by a pull upon the chain 20 to close the motor circuit. The insulating plate is held in proper position by reason of the fact that the lower end 25 thereof is engaged by the pin 23 and the strip 26 thereof extends through the guide-loop 27 provided upon the lower end of the switch-blade 28. When pressure is removed from the chain 20 and the lever 17 returns to normal position, the insulating strip 26 is again moved up and is inserted between the switch-arm 28 and the brush-holder 29, thereby opening the motor circuit.

The parts may be so adjusted that switch-blade 28 is in its closed position just prior to the pulley 18 coming into engagement with the belt 7. The motor can thus be running without any resultant drive of the machine. By a slight further pull upon the chain 20 the pulley 18 may be brought into engagement with the belt 7 and press the same into engagement with the pulley 6, thereby driving the pulley 16, which, as usual, is secured upon the end of the shaft 33 which extends longitudinally through the arm 34 of the machine. By suitably pulling upon the chain 20, the belt 7 may be more or less tightened with respect to the pulley 6, thereby controlling the speed at which the sewing machine is driven.

It will be understood that when the motor is utilized for operating the sewing machine the usual connection between the drive-wheel of the sewing machine and the treadle will be made inoperative, such connection, as is well known, consisting of a pitman extending from the treadle to the crank-pin of the drive-wheel. If it be desired to operate the machine by foot-power in the usual manner, this may be done merely by restoring the operative connection between the treadle and the drive-wheel and disconnecting the lower end of the chain 20 from the treadle. The position of the electric motor is such that it does not interfere with the driving of the machine by foot-power, though it may be readily removed from the table-top and with equal readiness be replaced when desired.

While I have shown and described a desirable commercial embodiment of the invention, it is obvious that other embodiments thereof may be devised without departure from the scope of the invention as defined in the accompanying claims.

What I claim is:

1. In a sewing machine motor, the combi- 130

- nation with an electric motor and a pulley driven thereby, of a switch for controlling the circuit of said motor, a lever for actuating said switch, and a belt-adjusting pulley carried by said lever.
2. In a sewing machine motor, the combination with an electric motor and a pulley driven thereby, of a driving belt adjacent to said pulley, a switch for controlling the circuit of said motor, a lever for actuating said switch, a pulley carried by said lever for moving said belt into operative engagement with said pulley, and means for operatively connecting said lever with the treadle of a sewing machine.
3. In a sewing machine motor, the combination with an electric motor, of a spring-tensioned switch-blade thereon tending to close the circuit of the motor; a lever also associated with said motor; and a member of insulating material arranged to be shifted by said lever either to permit the closure of said switch-blade or to hold the latter in its open position.
- 25 4. In a sewing machine motor, the combination with an electric motor, of a spring-tensioned switch-blade tending to press against one of the brush-holders of the motor; an insulating strip normally inserted between said blade and brush-holder; and a lever for withdrawing or inserting said insulating strip.
5. In a sewing machine motor, the combination with an electric motor and a pulley driven thereby, of a spring-tensioned switch-blade tending to close the circuit of the motor; a member of insulating material normally holding said blade in its open position; a lever for shifting said insulating material to permit the closure of said switch-blade; and a belt-adjusting pulley carried by said lever.
- 45 6. In a sewing machine motor, the combination with an electric motor and a pulley driven thereby, of a spring-tensioned switch-blade tending to press against one of the brush-holders of the motor; an insulating strip normally inserted between said blade and brush-holder; a lever for withdrawing or inserting said insulating strip; and a belt-adjusting pulley carried by said lever.
- 55 7. In a sewing machine motor, the combination with an electric motor, of a circuit-controlling switch located inside of the motor-casing, a lever pivoted upon the outside of the motor-casing for actuating said switch, and a belt-adjusting pulley carried by said lever.
- 60 8. In a sewing-machine motor, the combination with an electric motor, of a flexible switch-blade mounted inside of the motor-casing, said blade being shaped at its end into a guide; a strip of insulating material mounted to reciprocate in said guide to move said blade to either its open or closed posi-
- tion; a lever pivoted upon the outside of the motor-casing and provided with means for reciprocating said insulating strip; and a belt-adjusting pulley carried by said lever.
9. The combination with a sewing machine having a pair of pulleys and a belt connecting the two, of an electric motor and a pulley driven thereby, a lever provided with a belt-adjusting pulley and means whereby said lever may be actuated to move said belt into contact with said motor driven pulley to thereby drive said belt.
- 70 10. The combination with a sewing machine having a pair of pulleys and a belt connecting the two, of an electric motor and a pulley driven thereby, a lever provided with a belt-adjusting pulley and resilient means whereby said lever may be actuated to move said belt into contact with said motor driven pulley to drive said sewing machine at variable speeds.
- 75 11. The combination with a sewing machine having a table top, a pair of pulleys, one above and one below said table top and a belt passing through openings in said table top and connecting said pulleys, of a base resting on said table top, a motor slidably mounted on said base, and means adapted when operated to cause a relative movement between said motor and said belt whereby the latter may be driven by said motor.
- 80 12. The combination with the driving element of a sewing machine, of a motor and a pulley driven thereby, a lever, a belt-adjusting pulley carried by said lever, and normally out of operative engagement with said driving element, and means for operating said lever whereby said driving element may be moved into engagement with said first-named pulley.
- 85 13. The combination with the driving element of a sewing machine, a motor and a pulley driven thereby, of a lever, a belt-adjusting pulley carried by said lever, and means for operating said lever whereby said driving element may be moved into engagement with said first-named pulley, said lever also being provided with means adapted to control the flow of current to said motor.
- 90 14. The combination with the driving element of a sewing machine, of a motor provided with a driving pulley, and an idle pulley, said pulleys being positioned on opposite sides of said driving element and out of contact therewith, and means adapted to operate said idle pulley to move said driving element into engagement with said driving pulley.
- 95 15. In a motor of the type described, a driving pulley, and an idle pulley, and a tension member connected to said idle pulley to provide means whereby the operator may move said pulley into contact with the belt of a sewing machine to hold said belt in 100
- 105 110 115 120 125 130

variable speed engagement with said driving pulley.

16. In a device of the class described, an electric motor, sewing machine pulleys at a fixed distance from each other, a belt connecting said pulleys, a pulley mounted adjacent said belt and out of contact therewith and adapted to be driven by said motor, a

pivoted lever, and resilient means at the control of the operator for rocking said lever about its pivot to move said belt into driving engagement with said pulley.

In witness whereof, I hereunto subscribe my name this 17th day of June A. D., 1915.

CHESTER H. BEACH.
